HANDLE BAR

Bert J. Anderson, Hammond, Ind.

Application December 12, 1935, Serial No. 54,117

12 Claims. (Cl. 74—551.1)

This invention relates to an improvement in handle-bars and has for one of its principal objects the provision of means for producing an article of the kind described from a single sheet metal stamping.

A still further important object of advantage in the present invention resides in the provision of means for forming a downwardly projecting steering post receiving portion of the rear central part of the stamping.

An additional object of advantage and importance is the provision of loop means for receiving portions of the upper end of a steering post.

Another important object of the handlebar resides in the provision of means for interlocking the joined edges of the post receiving portion.

Additional objects of importance and advantage will be apparent from the following detailed description, reference being had to the accompanying drawings, wherein—

Fig. 1 is a top plan view of a handlebar which embodies the preferred form of the invention.

Fig. 2 is a front elevational view thereof.

Fig. 3 is an elevational view taken from the rear.

Fig. 4 is a vertical section taken on line 4—4 of Fig. 3.

Fig. 5 is a section, slightly enlarged, taken on line 5—5 of Fig. 3.

Fig. 6 is a bottom plan view of the handlebar shown in Fig. 1.

Fig. 7 is an elevational view of the lower end of the handlebar post joined to a fork post.

Fig. 8 is a section taken on line 8—8 of Fig. 7.

Fig. 9 is an elevational view of a handlebar post, showing a slight modification.

Fig. 10 is a vertical section taken on line 10—10 of Fig. 9, and

Fig. 11 is a vertical section taken on line 11—11 of Fig. 7.

As shown in the drawings:

The reference numeral 10 indicates in general the stamping from which the handle bar of the invention is formed. In the preferred embodiment of the invention, the entire handlebar, including the steering post receiving portion, is formed of a single stamping.

As is clearly shown in the drawings, the central portion of the handle bar is of greater diameter than either end 12 and the upper surface thereof is substantially flat and suitable to carry designs such as is indicated by the reference numeral 14, and reenforcing ribs 15.

Each end 12 of the handle bar is curved outwardly and rearwardly and a portion thereof

extending inwardly from each end is curled into tubular formation, as is best shown in Figs. 3 and 6, and is adapted to receive a grip or handle.

The front 16 and rear 18 edges of the stamping 10 are turned downwardly to add to the appearance and stiffness of the article.

A steering post receiving member 20 is produced by curling into tubular formation and turning downwardly the rear central portion of the stamping 10, as is best shown in Fig. 4.

The edges 22 of the member 20 are preferably provided with coacting tongues and notches which, when joined, as shown in Fig. 2, form a rigid joint.

Extending inwardly from the front of the member 20 and adapted to receive a portion of the upper end of a steering post is a loop 24. Where a single loop 24 is provided, it is preferably formed in the member 20 directly opposite the joined edges 22.

It will be apparent that where the handle bar of the present invention is used with a steering post 25 having a tongue 27 formed below the end of said post each inwardly projecting side 26 of the loop 24 forms a bearing surface for transmitting rotative force to the steering post.

In the preferred embodiment of the invention the loop or keeper 24 is formed by making a slit 29 transverse the longitudinal axis of the tubular member 20 and then spreading the edges thereof apart by forcing the upper edge inwardly, as is best shown in Figs. 4 and 11. However, any other suitable method may be employed in forming the loop, for example, two parallel slits 38 may be made in the member 20 as is best shown in Fig. 9, and the metal therebetween then forced inwardly to produce a loop or keeper as is clearly shown in Figs. 10 and 11. The loop thus formed is on the inner surface of the steering post receiving member 20 and is open at both top and bottom. This structure allows a tongue 27 of any length to be used in the assembly of the handle bar with a steering post. The particular structure shown in the modification allows a limited longitudinal adjustment of the telescoping parts 20 and 25 without withdrawing the tongue from the keeper.

Formed in opposed sides of the member 20 are bolt receiving openings 28. When assembled with a steering post, a bolt 31 in the openings 28 prevents longitudinal movement of the parts in relation to each other. In the preferred embodiment of the invention the metal immediately surrounding the openings 28 is raised to pro-

vide a flat surface 33 for the head and nut of the bolt 31.

It will be apparent that herein is provided a neat and attractive handle bar which is rugged and sturdy and which may be economically constructed of a single stamping without riveting or welding.

I am aware that many changes may be made and numerous details of construction varied throughout a wide range without departing from the principles of this invention and I, therefore, do not purpose limiting the patent granted hereon otherwise than as necessitated by the prior art.

15 1. I claim as my invention:

1. In a handle bar for a velocipede, a stamping having a downwardly extending rear central part, said part being of tubular formation, and tongue receiving means formed in said tubular formation, said tongue receiving means being formed by separating the edges of a slit in said tubular formation.

2. In a handlebar for a velocipede, a stamping having a downwardly extending rear central part, 25 said part being of tubular formation, and tongue receiving means formed in said tubular formation, said tongue receiving means being formed by depressing a portion of the tubular formation.

3. In a handlebar for a velocipede, a stamping having a downwardly extending rear central part, said part being of tubular formation, and an inwardly projecting loop formed in said downwardly extending central part, said loop having 35 an opening in the bottom thereof which is adapted to receive a portion of a fork post.

4. In a handlebar for a velocipede, a stamping having a downwardly extending rear central part, said part being of tubular formation, and an 40 inwardly projecting loop formed in said downwardly extending central part, said loop being formed by cutting two parallel slits and depressing the metal therebetween.

5. In a handlebar for a velocipede, a stamping 45 having a downwardly extending tubular member in the rear central portion thereof, and a transverse slit in the metal intermediate the ends of said tubular member, the upper edge of said slit projecting inwardly to form a loop.

50 6. In a handlebar for a velocipede, a stamping having a downwardly extending tubular member in the rear central portion thereof, a transverse strip of the metal intermediate the ends of said tubular member being depressed to form a loop on one side of said tubular member, and inter-

locking joined edges on the opposite side thereof.

7. In a handlebar for a velocipede, a stamping having a downwardly extending rear central portion, said rear central portion being curled into tubular formation, the edges of said tubular formation being interlockingly joined, and an indentation having an opening in the bottom 5 thereof in said tubular formation.

8. In a handlebar for a velocipede, a stamping having a downwardly extending rear central portion, said rear central portion being curled into tubular formation, the edges of said tubular formation being interlockingly joined, and an inwardly projecting loop formed in said tubular 10 formation.

15 9. In a handlebar for a velocipede, a stamping having a downwardly extending rear central portion, said rear central portion being apertured and curled into tubular formation, said tubular formation having a slot, the metal directly above 20 said slot being pressed inwardly, and the edges of said tubular formation being interlockingly joined.

10. In a handlebar for a velocipede, a stamping having a downwardly extending rear central portion, said rear central portion being apertured and curled into tubular formation, two of said apertures being on opposed sides of said tubular formation and in alignment, said tubular member being slotted and the metal between said 25 30 slots being pressed inwardly, and the edges of said tubular formation being interlockingly joined.

11. In a handlebar for a velocipede, a stamping, a tubular grip receiving formation on each 35 end of said stamping, an apertured tubular member extending downwardly from the rear central portion of said stamping, said apertures being on opposed sides of said tubular member and in alignment, and said tubular member being slotted 40 transverse the longitudinal axis thereof to provide means within said tubular member for securing a steering post against rotation.

12. A handlebar comprising a single stamping having a downwardly projecting tubular central 45 portion adapted to telescope a steering post, said tubular portion being apertured and slotted, said apertures being adapted to receive means for securing said handlebar to a steering post, and said slot providing means formed with portions of said stamping to coact with means on a steering post for causing said parts to rotate in unison.
